REMOTE STATION RECORDING

Kenneth J. Dunlap, Toledo, Ohio, assignor of one-third to Lionel L. Levy, and one-third to Fred M. Douglass, both of Toledo, Ohio

Application March 23, 1940, Serial No. 325,545

6 Claims. (Cl. 179—5.5)

This invention relates to telephone accessories operable for receiving and recording identification data.

This invention has utility when in connection with dial type telephones there may be failure to answer. Hereunder upon such failure, the one calling may leave identification for response call at the telephone which did not answer providing such has been pre-set to receive this information.

Referring to the drawings:

Fig. 1 is an end elevation of an accessory in proximity to a normal dial telephone say of the cradle type, parts being broken away;

Fig. 2 is a section on the line II—II, Fig. 1, showing the record delivery device at such receiving station;

Fig. 3 is a section on the line III—III, Fig. 1, showing the sequence control features for the record tape to be fed and the switches for action of the punch of Fig. 2 in making the record on such tape;

Fig. 4 is a wiring diagram with diagrammatic features of the interconnection mechanism on the feed; and

Fig. 5 is a fragment of the record, say code for identification.

Conduit 1 (Fig. 1) may bring in receiving lines to box 2, say for signal as a bell in calling a subscriber. From this box 2 conduit 3 may extend to cradle 4 having manually operable control means or dial 5 which may be operable at such station when head set 6 is lifted from the cradle 4 and such dial 5 operated in the calling of central or some other remote station out of central or some other station under the system. Herein from such cradle or dial carrier 4 conduit 7 extends to housing 2. The conduit 7 extends to terminals 9, 10 (Figs. 2, 3) on insulation block 11 carried by partition plate 12, anchored to the housing 6 by screws 13.

From the terminal 9 extends line 14 (Fig. 4) to contact 15 normally in switch closing position with contact 16 of line 17 to coil 18, thence past condenser 19 to line 20 in completing circuit to the terminal 10. This means that the one operating the dial 5 to call remote station ringer box 21 having dial 22 has this station 21 effective in completing at once the ringing circuit between the terminals 9, 10, to have the coil 18 operate solenoid 23 to withdraw terminal 24 from notch 25 in disk 26 fast to the shaft 27. On this shaft 27 there is located motor 28, preferably having a self-starting energy source as a spring type motor, or an electric motor which is to an ex-

tent wound by the electric current as of certain clock types. Accordingly, on this release of the disk 26 by the solenoid plunger 23, the motor 28 is effective to start this shaft 27 and through cam 29 acting on roller 30 thrust switch carrying stem 31 to open the switch 15, 16. In so doing, there is de-energizing of the coil 18 so that the plunger 23 rides against the disk 26 for single cycle operation of this disk 26, in that it effects a stop of such disk at once there is complete rotation, this stop being completed by this plunger 23 having its point 24 enter the recess 25.

In this starting operation, the cam 29 in its operation to open the switch 15, 16, simultaneously effects additional switching functions, in that the contact 15 is closed with contact 32 communicating by lines 33, 34, 35, with polarizing relay 36 having therewith condenser 31 as a bypass to minimize contact arcing adjacent this polarizing relay 36. The circuit for this relay 36 is completed by line 38 to contact 39 with which, through the action of stem 31, is brought contact 40 completing circuit by line 41 with the line 20. This means that the telephone line circuit which released the disk 26 by the operation of the solenoid 18, 23, is effective on the polarized relay 36. In energizing this relay, it is effective in operating switch 42 at such relay to line 43 and coil 44, from which extends lines 45, 46, to contact 47, in cooperation with which is thrust contact 48 by the switch device 31, thereby connecting line 49 which extends to terminal 50. Adjacent the terminal 50 is terminal 51 and from these terminals in the housing 6 there extends conduit 52 (Fig. 1) to energy source as battery 53 (Fig. 4). Accordingly, from this battery by the terminal 51 there extends line 54 to the line 34. This completes the booster or energizing circuit for the accessory as in conjunction with the receiving station telephone and with a power beyond that normally in the line to such remote station. This reserve power circuit from the line 54 may connect from the line 34 by line 55 to coils 56 in series, and from thence by line 57 to switch 58 as thrown by the coil 44 to complete circuit by line 58 therefrom to the line 46, thence to the contact 47 as abutting the contact 48 and by line 49 therefrom to the terminal 50. Condenser 57 is a bypass between the lines 46, 57, as to this switch 58. Accordingly, there is this energizing current from the battery 53 to operate the coils 56, herein shown as in series and effective to operate armature 60 against the action of spring 61 (Fig. 2) and thrust plunger 62 through

guide openings 63, 64, in acting on tape 65 (Fig. 4). This operation from the remote station is accordingly one transmitting the code impulses as coming to this accessory at the terminals 9, 10, which code impulses as fortified by the battery 53 actuate the cutting punch 62 on the tape 65 in marking such tape with notations 66 (Fig. 5) of the code identity.

The one having the accessory in the housing 8 at the receiving station may, through switch or manual control 67 (Figs. 1, 3, 4), cut in or cut out the functioning of this code receiver and recorder device as for such remote station. With this device 67 in holding position, say as against rotary blade or fan 68, functioning of the motor 28 for rotating the shaft 27 and the cam 29 may not occur. However, as such shaft 27 may be driven from the motor 28, it is effective through speed reduction transmission 69 to operate drum 70 (Fig. 2) having traction friction face thereon. The tape 65 as of onion skin or thin paper may be held in contact with such face through the action of spring 71 upon arm 72 and pivot bearing 73 for swinging roller 74 against the tape 65 and holding such against the feed roller 70. This tape is thus frictionally drawn from magazine reserve supply roll 75 having friction or resistance mounting hub 76 therefor to preclude excess unwinding at the pull operations of this feed roll 70. This strip of tape 65 from the roller 75 passes between die guides 63, 64, at which the spring 61 normally holds the armature 60 clear of the coils 56. This pair of coils 56 in their operation have a direct pull on this punch 62 in effecting the rapid code functioning or developing the marking 66 in the tape 65 as such tape is progressed by the feed roller 70. Slack against untoward feeding or pulling of the tape 65 is obtained by the out-of-line small idler or guide 77. This strip of code-carrying tape 65 emerges from the housing 8 at port 78, and as emerged therefrom may be torn by pulling against cutter 79. The single service or cycle operation of the motor 28 as determined by the plunger point 24 registering with the seat 25 permits the time interval for the calling station to effect the code setting or marking transmission even repetitively if desired. At the completion of the cycle independent of other conditions, the device is automatically cut out for a repetition of a succeeding cycle of this functioning. Accordingly, the one at the station called, who has operated the selective cut-in 67, may thus have a record of the calls to which attention is to be given. However, if it be not desired to have these calls come in, manual controller 67 may be in the break position as to the motor 28 and thus allow the phone to function as normally in the matter of response and absence of response.

Herein with the controller 67 say to cut in an electric control, there may be a distinction in the busy call as to the one calling or non-answering, so that the remote station may thus be informed that a reminder in the way of code identification data may be supplied to such remote station as unanswering the call, so that as subsequent attention is given the remote station phone the return call may be placed.

In the carrying out of the invention herein, there is simplicity with minimum of mechanical or moving parts required. There is a compact accessory in the housing 8 which readily functions as connected up with the increased energy source, as the battery 53. The dialing of the calling station is as normal, and when the sta-

tion does not answer such calling station may re-dial as a signal for having such re-dialing not of the identity for such remote station as being called but say for the calling station or some station as to which it is desired to have the unanswering one respond. This means that the selection and full control of the code emanates from this one calling to the one failing to answer and is effected by having such remote station dialing, as specially calling, perform the full sequence of code identification. The only mechanical parts required are the feed for the tape hereunder to receive the code and incidental thereto the switches functioning in determining the sequence.

Fixed with the terminal or stem 24 is slide 80, which slide, as the stem 24 is in the notch 25, has its terminus 81 in position to intercept the fan 68. In practice this means that at once the terminal 24 enters the notch 25, driving load is taken off the shaft 27 due to the fact that this slide terminus 81 intercepts the fan blade 68.

What is claimed and it is desired to secure by United States Letters Patent is:

1. The combination with an accessory for a dial type telephone receiving station embodying a unit, controllable connections for placing said unit for operation in a circuit of said receiving station, a housing for the unit embodying a motor, record feeding means, a receiving station controller for rendering the motor operable in response to call for said receiving station, a calling station determining the release of the motor at the receiving station for the motor to operate the feeding means, identification means controllable at the calling station, a marker for records from the feeding means, switch means for connecting the marker for response to the identification means, an operator for the switch means, and a release for the operator.

2. The combination with an accessory for a dial type telephone receiving station embodying a unit, controllable connections for placing said unit for operation in a circuit of said receiving station, a housing for the unit embodying a motor, record feeding means, a receiving station controller for rendering the motor operable in response to call for said receiving station, a calling station determining the release of the motor at the receiving station for the motor to operate the feeding means, code identification impulse means controllable at the calling station, a marker for records from the feeding means, switch means for connecting the marker for response to the identification means, an operator for the switch means, and a solenoid release for the operator.

3. The combination with an accessory for a dial type telephone receiving station embodying a unit, controllable connections for placing said unit for operation in a circuit of said receiving station, a housing for the unit embodying a motor, record feeding means, a receiving station controller for rendering the motor operable in response to call for said receiving station, a calling station determining the release of the motor at the receiving station for the motor to operate the feeding means, code identification impulse means controllable at the calling station, impulse responsive means, marking means operable by the impulse responsive means, switch means, a cam operable by the motor, a solenoid for releasing the cam for cutting in the switch means during the release of the motor for cycle of operation and during which operation impulse means may

mark on a record as actuatable from the feeding means.

4. The combination with an accessory for a dial type telephone receiving station embodying a unit, controllable connections for placing said unit for operation in a circuit of said receiving station, a housing for the unit embodying a partition in the housing, on one side of the partition record feeding means, on the other side of the partition a motor for the feeding means, a receiving station controller for rendering the motor operable in response to call for said receiving station, a calling station determining the release of the motor at the receiving station for the motor to operate the feeding means, code identification impulse means controllable at the calling station, impulse responsive means, marking means operable by the impulse responsive means, switch means, a cam operable by the motor, a solenoid for releasing the cam for acting on the switch means through release of the motor for cycle of operation, said switch means cutting in the impulse responsive means for operating the marking means on a record as actuatable from the feeding means.

5. The combination with an accessory for a dial type telephone receiving station embodying a unit, controllable connections for placing said unit for operation in a circuit of said receiving station, a housing for the unit embodying a partition in the housing, on one side of the partition record feeding means, on the other side of the partition a motor for the feeding means, a receiving station controller for rendering the motor operable in response to call for said receiving station, a calling station determining the release of the motor at the receiving station for the motor to operate the feeding means, code identification

impulse means controllable at the calling station, impulse responsive means, marking means operable by the impulse responsive means, multiple switch means, a cam operable by the motor, a solenoid for releasing the cam for acting on the switch means during said release of the motor for a cycle of operation and including sequence control means effective after the motor is started on said cycle for cutting in the impulse responsive means for recording transmission from the calling station operation of the marking means on a record as actuatable from the feeding means.

6. The combination with an accessory for a dial type telephone receiving station embodying a unit, controllable connections for placing said unit for operation in a circuit of said receiving station, a housing for the unit embodying a partition in the housing, on one side of the partition record feeding means, on the other side of the partition a motor for the feeding means, a receiving station controller for rendering the motor operable in response to call for said receiving station, a calling station determining the release of the motor at the receiving station for the motor to operate the feeding means, code identification impulse means controllable at the calling station, impulse responsive means, marking means operable by the impulse responsive means, a supplemental energy source, multiple switch means, a cam operable by the motor, a solenoid for releasing the cam for acting on the switch means and during said release of the motor for a cycle of operation cutting in the energy source for the impulse responsive means to record from the calling station operation upon the marking means in producing a record as actuatable from the feeding means.

KENNETH J. DUNLAP
